(57) **CLAIM**

The ornamental design for a folding stand fan, as shown and described.

DESCRIPTION

FIG. 1 is a front, top, right perspective view of a folding stand fan showing my design therefor;
FIG. 2 is a top plan view thereof;
FIG. 3 is a bottom plan view thereof;
FIG. 4 is a left side elevational view thereof;
FIG. 5 is a right side elevational view thereof;
FIG. 6 is a front elevational view thereof;
FIG. 7 is a rear elevational view thereof;
FIG. 8 is a top, right, front perspective view thereof showing the same design in the different position;
FIG. 9 is a top plan view of the position shown in FIG. 8;
FIG. 10 is a bottom plan view of the position shown in FIG. 8;
FIG. 11 is a front elevational view of the position shown in FIG. 8;
FIG. 12 is a rear elevational view of the position shown in FIG. 8;
FIG. 13 is a side elevational view of the position shown in FIG. 8; and,
FIG. 14 is an opposite side elevational view of the position shown in FIG. 8.
Throughout the design, the broken lines are environment and form no part of the design.
